KNIFE

Robert W. Lowry, Minneapolis, Minn.

Application February 14, 1944, Serial No. 522,233

5 Claims. (CL 30—175)

This invention relates generally to cutlery and particularly to knives used for culinary purposes.

The main object of this invention is to construct a knife which will protect the thumb of the user when cutting vegetables between the knife and the thumb.

The second object is to construct a knife of the class described which will facilitate the preparation of vegetables, rendering unnecessary the usual care required in the dicing of vegetables.

The third object is to construct a knife of the class described which will accomplish the purposes set forth without detracting from the use of the knife for ordinary paring purposes.

These and other objects are accomplished in the manner set forth in the following specification, as illustrated in the accompanying drawing, in which:

Fig. 1 is a side elevation of the device showing same being used to dice vegetables.

Fig. 2 is a plan of Fig. 1.

Fig. 3 is a side elevation of the knife in position for paring.

Fig. 4 is a transverse section taken along the line 4—4 in Fig. 3.

Fig. 5 is a section taken along the line 5—5 in Fig. 2.

Fig. 6 is a transverse section through a modified form of thumb guard.

Fig. 7 is a transverse section through a second modification of the thumb guard.

Similar numerals refer to similar parts throughout the several views.

Referring in detail to the drawing, there is shown a blade 10 whose broadened portion 11 is provided with the two rivet holes 12 for the rivets 13, and an intermediate hole 14 for the rock shaft 15, whose reduced portion 16 journals in the hole 14. Secured on the reduced portion 16 is a cam 17 whose flat side 18 engages a spring 19 when the knife is in a dicing position, or it may engage the face 20 when the knife is in a paring position.

The spring 19 is preferably held in the slot 19A formed in the end of the broadened portion 11. The metal 22 on one side of the slot 19A projects beyond the end 23 of the side 24 in order that the surface 25 may be used as a stop. The rock shaft 15 has formed on one end a flattened section 26.

Wooden handle members 27 and 28 are provided, the former having an enlarged recess 29 around the hole 14 adapted to receive the flange 30 which is formed on one end of the rock shaft 15, while the handle member 28 is hollowed out 55

to provide clearance for the cam 17 and the spring 19.

Mounted on the flattened section 26 is an arm 31 and mounted on the portion 16 is an arm 32. The arms 31 and 32 are joined by the thumb piece 33. In the form of the device shown in Fig. 6 the thumb piece 33A is partially slotted to permit the knife to sever the vegetable without touching the metal or the thumb.

10 In the form shown in Fig. 7 the thumb piece 33B is curved for the same purpose, namely to permit the vegetable to be severed without having the knife touch the metal or the finger.

The operation of the device is as follows: Assuming that the parts are in the position shown in Fig. 1, the user merely presses the thumb 34 against the thumb guard 33 causing the vegetables 35 to be severed by the cutting edge 36 of the blade 10, releasing the thumb pressure and makes way for another portion of vegetable to be diced. It will be noted that while this is taking place, the spring 19 is either riding on the flat surface 18 or on the rounded edge 37 of the cam 17.

20 When the knife is to be used for paring, the thumb piece 33 is moved to the position shown in Fig. 3, toward which position it is urged by the spring 19 which is now contacting the face 20 of the cam 17.

25 While I have thus illustrated and described my invention, it is to be understood that I do not intend to be limited to the precise form shown herein, but I do intend to cover all such modifications and forms of the device as fall fairly 30 within the appended claims.

I claim:

1. A knife having a combination cutting blade, handle for holding said blade, a yieldable thumb piece mounted in the path of the cutting blade adjacent to said handle, a spring for urging the thumb piece away from the cutting edge and means for urging said thumb piece against the remote end of the handle when moved away from said blade a distance which is greater than the amount it would be moved by said spring when dicing, for the purpose of leaving the knife in a paring position.

40 2. In a knife, a combination of a thumb piece having a pair of arms extending from one end thereof, a knife having its handle pivotally mounted between said extending arms, a spring actuated cam for urging the thumb piece away from said blade and a cam forming a part of the pivotal connections between said knife and thumb piece whereby the movement of said thumb piece

away from said blade to a distance greater than is produced by the spring and cam will cause said thumb piece to be urged toward the opposite end of the handle.

3. In a device of the class described, the combination of a thumb piece having a pair of parallel arms forming a fork thereon with a knife having its handle pivotally mounted between the ends of said fork, a spring for urging said thumb piece into a spaced relationship with said knife blade and cam means for overcoming the action of said spring and causing same to occupy a new relationship to said blade wherein said thumb piece forms an extension for the handle end of said knife.

4. A knife having a handle, a blade at one end of said handle having a stop formed at the butt end thereof extending beyond the end of said handle, a transverse rockable pivot mounted in said handle, a thumb piece having a pair of arms

5 mounted on said rockable pivot on opposite sides of said handle, a flat sided cam on said rockable pivot and a spring engaging said cam adapted to hold said thumb piece against said stop and at a point near the cutting edge of said blade.

5. In a device of the class described, the combination of a thumb piece having a pair of longitudinal arms formed thereon in parallelism with each other, a knife having a pin extending transversely through the handle thereof forming a pivot for said arms, a cam on said pin having flat sides thereon, a spring in said handle engaging the flat sides of said cam whereby said thumb piece may be urged against the end of said handle to form an extension therefor, or in the opposite direction to position spaced from the cutting edge of said knife.

ROBERT W. LOWRY.
